US0D1025209S

(12) United States Design Patent (10) Patent No.: US D1,025,209 S
(45) Date of Patent:  Apr. 30, 2024

(54) LABEL

(71) Applicant: Coravi Capital Limited, Limassol (CY)

(72) Inventor: Serhii Sukhyi, Kropyvnytskyi (UA)

() Term: 15 Years

(21) Appl. No.: 35/516,591

(22) Filed: Nov. 29, 2022

(80) Hague Agreement Data

Int. Filing Date: Nov. 29, 2022

Int. Reg. No.: DM/227419

Int. Reg. Date: Nov. 29, 2022

Int. Reg. Pub. Date: Mar. 17, 2023

(51) LOC (14) Cl. 19-08
